PIVOTAL FRAME WRINGER

Nicholas L. Etten, Waterloo, Iowa

Original application April 11, 1941, Serial No. 388,024. Divided and this application September 3, 1943, Serial No. 501,181

3 Claims. (Cl. 68—269)

My invention relates to clothes wringers of the type mounted on power driven domestic clothes washers.

This is a divisional application of my application Serial No. 388,024 filed April 11, 1941.

The particular object of the invention is to provide a roll stop mechanism operable to stop the rolls upon pivotal movement of the wringer by pressure applied on any part of the wringer. I am aware that mechanisms have been made involving pivotal movement of the wringer in relation to the gear head or such similar arrangement, but such devices involve separating the gear head from the wringer and supporting the wringer on pivotal links or the like, which introduces complications in structure which I desire to avoid.

Another object of my invention is to provide means to pivotally mount a practical, unitary gear head and wringer mechanism by means which will provide a stoppage of roll rotation upon pivotal movement of the complete wringer.

I will disclose and describe the device in the following description and drawings in which:

Fig. 1 is a front elevation view of the wringer complete in operating position, and

Fig. 2 is a top plan view of the same wringer as shown in Fig. 1 with the off or released position of the wringer indicated in broken dot-dash outline.

Now referring to the drawings, and at the outset to Fig. 1, I designate the lower frame housing, the wringer and gear head complete by the numeral 10, and the upper frame by the numeral 11. Conventional wringer rolls 12 and 13 are mounted in conventional bearings in the lower frame as shown. The inner end of the top frame is mounted on the lower frame by a stationary stab clip 13, and the outer end of the upper frame is mounted on the lower frame by a pressure reset lever 14 and the toggle lever 15, the reset lever being pivotally mounted on the upper frame 11 by the pivot 16 and attached to the toggle lever 15 by the pivot 18, the toggle lever 15 pivoting on the lower frame 10 by the pin 17. This is a conventional form of frame attachment well understood in the art and will not be described in further detail except to explain that the toggle lever 15 in closed position is a stable toggle which is released by moving the reset lever 14 outwardly until the toggle pin 18 is thrown outwardly beyond the pin 17 when the entire upper frame will be released by the movement of the toggle 15. Roll pressure is provided by a conventional spring 19 held in pressure sustaining position by the adjustment screw 20.

The complete wringer is pivotally supported on an indexing flange casting 20' and interposed between the flange 20' and the frame 10 is a pivot plate 21, to which the frame 10 is pivotally attached by the pivot pin 22 on the inner end of the wringer. The wringer is normally held in fixed position by the taper plunger 23, which is held in the mating notch 24 of the pivot plate 21 by the spring 25 around the plunger rod 26. The plunger rod 26 is slidably mounted in bearings 27 and 28. By this structure it will be understood that pressure applied on the frames 10 or 11 will tend to pivot the frame 10 around the pivot pin 22 and by the tapered notch 24 force the plunger 23 outwardly against the spring 25, whereupon the rod 26 will be moved outwardly, pushing the reset lever 14 with it to release the toggle 15 and with it the top frame 11.

Excess movement of the frame 10 is prevented by stops 29 and 30 on the pivot plate 21, as clearly shown in Fig. 2. It will be appreciated that the wringer is held in central position on the pivot plate 21 by the co-action between the pivot pin 22 and the taper plunger 23 in the notch 24.

Now referring again to Fig. 1, the drive to the gear head is provided by conventional drive shaft 31 rotatably mounted in bearings 32 and 33 in the indexing flange casting 20'. The shaft 31 is held by the bearings 32 and 33 in the flange casting 20' because it is necessary to provide a slotted opening 34 in the bottom of the frame 10 by reason of the relative movement between the frame 10 and the pivot plate 21. The drive shaft 31 mounts a conventional spur gear 35 in the gear head which meshes with a companion spur gear 36 on the vertical shaft 37. The gear 36 is fixed to the shaft 37 and drives the clutch 38 by means of a key 39 on which the clutch is slidable. The key 39 holds the loose lower gear 36' and the upper spur gear 40 in operating relationship by co-action with the pin 40' and the collar 37'. The clutch 38 is provided with internal gear openings 41 and 42 mating with the inner ends of the respective gears 40 and 36', whereby when the clutch 38 is actuated in one direction or another, the internal gears 41 and 42 will engage the ends of the respective gears 40 and 36', whereby driving relationship with the shaft is established and the mating face gear 43 may be driven in either direction at the will of the operator by moving the handle 44 to force the eccentric pin 45 either upward or downward to establish driving relationship with either gear 36' or 40. This is a conventional form of drive gear

head which is well understood in the art, and is believed to require no further description.

As is well understood in the art, the lower frame must be indexed pivotally around the washing machine to provide facilities to wring from out of the washing machine or out of associated rinse tubs. Such indexing is provided in my device by an indexing mechanism mounted on a bracket 46 attached to the pivot plate 21. A release latch 48 is pivotally attached to the bracket by the pin 47 and contacts an indexing pin 49 urged upwardly by the spring 50 as illustrated. The pin 49 is adapted to engage selectively in notches 51 in the periphery of the flange 29' and in coating recess in the plate 21. By moving the index lever upward the indexing pin 49 is moved down or out of contact with the indexing notches 51 disposed around the flange of the member 20, and thereupon the entire wringer with the pivot plate 21 may be indexed to any required index notch 51, and the wringer disposed in proper position as required by the operator.

Now referring to Fig. 2, it will be appreciated that when the wringer frame 10 is moved pivotally around the pin 22 on the pivot plate 21, and the release plunger 28 has been actuated to release the reset lever 14 and the top frame 11, the entire wringer, including the gear head, will be pivotally moved around the pin 22, as shown in broken dot-dash outline in Fig. 2. When such movement occurs in a backward direction, the spur gear 36 will assume the position shown in dot-dash outline at B. It will be noted that such pivotal movement around pivot point 22 will move the spur gear 36 out of engagement with the spur gear 35, as clearly shown in dot-dash outline B, and thereupon the drive to the rolls will be interrupted and therefore the rolls will be stopped from power rotation. Similarly, upon reverse movement of the spur gear 36 to the point F forwardly, the same interruption of the roll drive occurs, and, therefore, roll stop will be accomplished by pivotal movement of the wringer in either direction.

It will be appreciated that the force required to accomplish the pivotal movement as above described, may be varied by adjusting the tension of the spring 25, or angularity of the plunger 23 and its companion tapered notch 24.

Some of the structure disclosed herein is claimed in application No. 501,180, filed September 3, 1943.

Having thus described my invention, I claim:

1. In a wringer, the combination of a wringer frame, a plurality of coating rolls rotatably mounted in the frame, a drive shaft, drive gearing for the rolls and operatively connected with

the drive shaft, a gear housing enclosing the gearing and connected with the wringer frame, mounting means for the gear housing and wringer frame including a support and a pivotal connection between said support and the gear housing spaced laterally from the axis of the drive shaft for swinging movement of the gear housing and wringer frame eccentrically relative to the drive shaft, and releasably connectible means between the drive shaft and the gearing arranged for driving engagement between the drive shaft and the gearing when the wringer frame is in one position relative to the mounting support and being disengaged from driving engagement therebetween upon lateral swinging movement of said frame relative thereto.

2. In a wringer, the combination of a wringer frame, a plurality of coating rolls rotatably mounted in the frame, an upright supporting column having a drive shaft extending therethrough, mounting means for the wringer frame including a support carried by the supporting column, means mounting the wringer frame on said support and having a pivotal connection with said support spaced laterally from the axis of the drive shaft for swinging movement of the wringer frame eccentrically relative to the drive shaft, and gearing connecting the rolls with the drive shaft and including a pair of gears one mounted on the drive shaft and the other fixed relative to the frame in position for intermeshing engagement when the wringer frame is in one position and out of intermeshing engagement upon lateral swinging movement of the frame to another position relative to the mounting means.

3. In a wringer, the combination of a wringer frame, a plurality of coating rolls rotatably mounted in the frame, a drive shaft, drive gearing for the rolls and operatively connected with the drive shaft, a gear housing enclosing the gearing and connected with the wringer frame, mounting means for the gear housing and wringer frame including a support and a pivotal connection between said support and the gear housing spaced laterally from the axis of the drive shaft for swinging movement of the gear housing and wringer frame eccentrically relative to the drive shaft, said gearing including a pair of gears interconnecting the drive shaft and the rolls, said pair of gears being mounted in the housing in position for intermeshing engagement when the wringer frame is in one position relative to the mounting support and relatively movable out of intermeshing engagement upon lateral swinging movement of the frame relative thereto.

NICHOLAS L. EITEN.
